8 Claims. (Cl. 222—101)

Hitherto it has been necessary, as a rule, to pack up sand filling compound, so called sand putty, and other paste-like or viscous materials in sheet-metal canisters which can be scraped clean from their contents in conjunction with the emptying operation. However, the cost of procuring canisters is high, which tends to increase the selling price of the canned product, and difficulties will also be encountered in connection with disposal of the bulky canisters after emptying their contents. Therefore, it has long been desired to enable the sheet-metal canisters used heretofore to be replaced by bags or sacks, such as plastic coated paper bags, for example, which are cheaper to procure than canisters and can more easily be disposed of after emptying their contents. However, the idea of packing sand putty and similar paste-like or viscous masses in bags could not be practically realized up till now due to the difficulties of emptying the bags of their frequently greasy contents.

The invention has for its object a machine for emptying bags made of paper or the like and containing a paste-like or viscous material, for example sand putty.

A method according to the invention resides in placing the bag to be emptied in a horizontal position on a preferably plane table, opening the bag at one end, for instance by making a transverse cut in the uppermost wall of the bag by means of a knife or other tool, and emptying the bag of its contents by moving a roller under pressure against the bag from its closed end towards its opened end, the roller then pressing the bag flat against the table while forcing its contents forwards towards and out through the opened end, whereby the bag is forcibly and completely emptied of its contents.

A machine provided according to the invention comprises a preferably plane and rectangular table adapted to receive on it the bag to be emptied, and a roller resiliently urged against the top face of the table and adapted to be rotated by a hand crank or the like so as to be rolled over the table from one end of the latter towards the other. According to a preferred embodiment, the forces due to the roller pressure are taken up by a reaction roller disposed beneath the table and rolling in contact with the bottom face of the table, said reaction roller serving at the same time to guide the pressure roller to prevent the latter from skewing relative to the longitudinal direction of the table.

The invention will now be described more in detail with reference to the accompanying drawings in which FIG. 1 is a perspective view of the bag-emptying machine according to one embodiment of the invention mounted on the pressure vessel of a travelling spray painting equipment, while FIG. 2, also in perspective view both on a larger scale, shows the emptying machine more in detail.

In the drawings, numeral 10 designates the table for receiving thereon the bag to be emptied, numeral 11 the pressure roller over the top face of the table, and numeral 12 the reaction roller rolling in engagement with its bottom face. The table 10 comprises a rectangular sheet-metal plate 13 reinforced at its longitudinally extending edges by two angle irons 14 welded to the bottom face of the plate. The rollers 11 and 12 are mount-

2

ed in a frame comprising two lateral metal guide plates 15 interconnected by two cross-bars 16 and each formed at its top edge with a channel-shaped guideway 17 which, with clearance, receives the depending flange of the corresponding angle iron 14. The journal pins 18 of the reaction roller 12 are mounted in top-open bearings 19 which are welded to the outer face of the lateral frame plates, respectively. Also welded to the outer face of each plate 15 is a vertically disposed guide sleeve 20 in which a cylindrical rod 21 is slidable in its longitudinal direction. Welded to the end of the rod 21 projecting upwards from the guide sleeve is a bottom-open bearing 22 for the corresponding journal pin 23 of the pressure roller 11. Compression coil springs 24 slid onto the ends 15 of the respective rods 21 projecting downwards from the guide sleeves 20 and compressed between the guide sleeve and a nut 25 screwed onto the lower end of the rod, maintain the two rollers 11 and 12 resiliently in engagement with the top and bottom faces, respectively, of the table 10.

Keyed onto the ends of the respective journal pins of pressure roller 11 and reaction roller 12 are identical gears 25, by which the two rollers are interconnected to be rotated in common and in opposite senses. One journal pin of pressure roller 11 is extended beyond the gear 25 and carries a hand crank 26 by means of which the pair of rollers 11, 12 can be rotated to move the pressure roller 11 over the top face of table 10 while exerting resilient pressure on the same, and to move the reaction roller 12 in engagement with its bottom face. Both rollers are covered by a coating of rubber or other resilient material having a great coefficient of friction relative to steel.

FIG. 1. shows the bag-emptying machine mounted on the pressure vessel 28 of a travelling spray painting apparatus. The comparatively small charging hole of the pressure vessel 28 is adapted to be closed by a lid 29. The table 10 carries at its end disposed above the charging hole a pivotally retractable filler funnel 30 the top opening of which has a width which is suitably equal to that of the table. The straight forward edge of the funnel 30 suitably projects inward beneath the table plate 13 to engage an abutment disposed on the bottom face thereof, when the funnel is in its operating position, as shown in the drawing.

The mode of operation of the emptying machine will appear clearly from FIG. 1. By turning the hand crank 26 counter-clockwise, the machine is first moved to the limit position at the end of table 10 opposite to that of the funnel 30, as shown in the drawing. The bag 31 to be emptied is placed on the table, and with one end of the bag disposed at the opening of the funnel 30. At the latter end of the bag a transversely extending cut 32 of a suitable length is made. At its other end, the bag 31 is flattened by hand, thereby possibly causing a portion of the contents of the bag to be pushed out through the slit 32. Thereafter, the hand crank 26 is turned clockwise, the pressure roller 11 then entering onto the bag 31, pressing the two sides of the bag together and pushing, during its rolling movement, the contents of the bag forward towards and out through the slit opening 32, thereby completely emptying the bag of its contents.

The invention is not restricted to the embodiment shown in the drawings, various modifications being conceivable within the scope of the invention.

What I claim is:

1. Apparatus for pressing a paste-type material from a pliable bag; comprising, a table mounted in a fixed, horizontal position and adapted to support said bag thereon; guide means slidably mounted on said table and adapted to move along said table; reaction roller means

fixedly mounted in said guide means for rotation therein and transversely disposed in contact with the lower surface of said table; pressure roller means transversely disposed in contact with the top surface of said table above said reaction roller; means for maintaining said reaction roller and said pressure roller in engagement with said table, including, spring means resiliently urging said pressure roller against said table; and roller advancing means operatively connected to said pressure roller and said reaction roller and adapted to turn said rollers in opposite directions and advance said rollers along said table by the frictional engagement of one of said rollers with said table.

2. Apparatus in accordance with claim 1 wherein the table has a pair of downwardly depending flanges along its opposing sides and the guide means includes a pair of generally U-shaped, elongated channels adapted to receive said flanges and slide therealong.

3. Apparatus in accordance with claim 2 wherein the guide means includes a pair of plates depending downwardly from the channels and the reaction roller is rotatably mounted in said plates.

4. Apparatus in accordance with claim 1 wherein the spring means resiliently urges the pressure roller against the table through the guide means.

5. Apparatus in accordance with claim 4 wherein the guide means are mounted beneath the table and the spring means includes a vertically-disposed sleeve fixedly mounted on the guide means, a vertically-disposed shaft fixedly connected to the pressure roller and slidably extending downwardly through said sleeve and a helical

spring mounted on the lower, free end of said sleeve and biased against the bottom end of said sleeve.

6. Apparatus in accordance with claim 1 wherein the roller advancing means includes gear means operatively connecting the rollers and crank means for turning one of said rollers.

7. Apparatus in accordance with claim 1 wherein a funnel means is mounted at one end of the table and is adapted to receive the paste-type materials pressed from the bag and direct it downwardly.

8. Apparatus in accordance with claim 7 wherein the funnel means is pivotally mounted on the table to rotate about a horizontal axis.
